UNITED STATES PATENT OFFICE.

DUNCAN KENNER, OF NEW ORLEANS, LOUISIANA.

WIRE-BINDING DEVICE.

Application filed July 11, 1922. Serial No. 574,202.

To all whom it may concern:

Be it known that I, DUNCAN KENNER, a citizen of the United States of America, and a resident of New Orleans, parish of Orleans and State of Louisiana, have invented a new and Improved Wire-Binding Device, of which the following is a description.

My invention relates to a device to bind or fasten any material with wire such for example, as binding rubber hose to a pipe or fitting, fastening yarn on a handle as in making mops, fastening wire about a barrel to strengthen the same, and for numerous like uses where a firm and tight binding of the wire is required.

The general object of my invention is to provide a device for effecting a secure binding of wire with little expenditure of strength and with facility.

The manner and means whereby the above and other objects are attained will clearly appear as the description proceeds.

Reference is to be had to the accompanying drawings forming a part of this specification, it being understood that the drawings are merely illustrative of one example of the invention.

Figure 1 is a plan view of a wire binding device embodying my invention showing the same in use;

Figure 2 is a section on the line 2—2, Figure 1;

Figure 3 is a section at right angles to Figure 2 and indicating by dotted lines the position of the device after having been rocked for bending the tightened wire;

Figure 4 is a perspective view of an end of the wire binder.

In carrying out my invention in accordance with the illustrated example, a tubular element 10 is provided, the bore 11 of which is advantageously cylindrical at its upper end and slightly tapered preferably at its forward or lower end, the intermediate portion of the bore tapering pronouncedly toward the forward end and therefore flaring upwardly.

A wire winding shaft or drum 14 is provided which extends across the bore 11 at the cylindrical portion 12 and has bearings in depressions 15 in the upper edge of element 10. A transverse hole 16 is formed in the shaft 14 for the passage of the wire end therethrough as further referred to hereinafter. A handwheel 17 or other grasping

device for turning the shaft 14 is provided at one end of the latter. A handle 18 is secured preferably detachably to the element 10 at a side thereof and for convenience of manipulating the device, said handle is disposed at right angles to the axis of the shaft 14. In the illustrated example a threaded stud 19 on the forward end of the handle engages a threaded hole in the thickened portion 20 of element 10.

In the described device the element 10 is tapered exteriorly and particularly so at its forward end the taper in practice being sufficient to permit the device to be rocked bodily after the wire is tightened to a position to one side for fastening the tightened wire.

In the use of the above described device a proper length of the binding wire A is wound about the material to be bound as for example the yarn B on a mop handle indicated at C. For the binding of the wire one end is formed with a hook a and after being wrapped about the material to be bound the wire is passed through the hooked end a and through the bore 11 from the front end 13. The end of the length of wire is then passed through the transverse hole 16 in winding shaft 14 and said shaft is turned by grasping the wheel 17 to wind the wire on said shaft. The winding of the wire on the shaft tightly will draw the wire through the hooked end a and bind it tightly about the material B. The wire having been wound and tightened the complete device is rocked bodily with the front end as a center in a direction to bend the same adjacent to the hook a and form a second hooked end thereon interlocking with the hook A after which the surplus wire may be snipped off.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. A wire binding device including an element having a bore therethrough and adapted at its front end to bear against the material to be bound, said element tapering toward the front end thereof, and a wind-

- ing element supported on said first element and adapted to draw tightly the wire when wound about the article to be bound and passed through said first element to the winding element, said binding device being adapted to be bodily rocked with its tapered forward end as a center of movement for bending the bound wire for fastening the same tightly.
- 10 2. A wire binding device of the class described comprising a tubular element adapted to have a binding wire passed therethrough, a winding element disposed

transversely across the bore of said first element, and a handle on said element at 15 right angles to the said winding element.

3. A wire binding device comprising a tapered tubular element adapted to have binding wire passed therethrough and having notches forming bearings at an end of 20 said element, a shaft having a transverse hole therethrough for the passage of the terminal of a binding wire, means to turn said shaft, and a handle on said element at right angles to said shaft.

DUNCAN KENNER.
